(No Model.)

O. F. COY.

DRIVING REIN.

No. 289.072.

Patented Nov. 27, 1883.

WITNESSES:

INVENTOR:

Niles H. Phillips OSCAR F. COY,
Willie C. Meagher by Franklin Scott, Atty.

UNITED STATES PATENT OFFICE.

OSCAR F. COY, OF NORTH BENNINGTON, VERMONT.

DRIVING-REIN.

SPECIFICATION forming part of Letters Patent No. 289,072, dated November 27, 1883.

Application filed October 12, 1883. (No model.)

To all whom it may concern:

Be it known that I, OSCAR F. COY, of North Bennington, in the county of Bennington and State of Vermont, have invented certain Improvements in Driving-Reins, of which the following description, in connection with the accompanying drawing, constitutes a specification.

This invention has for its object to provide the driving-reins of harness with improved means for preventing their slipping through the hands of the driver when in use; and it consists in the employment of a duplex strap or rim instead of a single strap, between which duplex parts are interposed hand-loops, as will hereinafter be more fully set forth.

The drawing fully explains the invention, which consists in making that part of an ordinary driving-rein which comes within reach of and is grasped by the hand in two strips, B and C, and interposing between them, at convenient distances, hand-loops D and D. The loops D D may be either of leather, metal, or any other suitable material; but however made, they are fastened or secured, as at f f, to both straps B and C.

The principal rein, A, may be made of a single strap of leather, split at its rear part forward up to the point e; or it may be made of two thin straps stitched or otherwise united, except where left separate for the insertion of the hand-loops D D.

The above-described construction prevents the rein from gradually working through and out of the grip of the hand of the driver, and also affords means for the driver obtaining a sure hold of the reins in cases of emergency.

I claim—

A driving-rein, of which the hand or rear parts are composed of duplex straps having interposed between them hand-loops, substantially as described, to which said duplex straps are attached, for the purposes set forth.

In testimony whereof I have hereto subscribed my name, at North Bennington, Vermont, this 8th day of October, A. D. 1883.

OSCAR F. COY.

In presence of—

FRANKLIN SCOTT,
WILLIS H. PHILLIPS.